UNITED STATES PATENT OFFICE.

GEORGE LAWRENCE FISK, OF ELLISVILLE, ILLINOIS, ASSIGNOR OF ONE-HALF TO ABRAHAM BROKAW, OF ELLISVILLE, ILLINOIS.

DESIGN FOR A CHICKEN-FOUNTAIN.

SPECIFICATION forming part of Design No. 35,532, dated December 31, 1901.

Application filed September 30, 1901. Serial No. 77,161. Term of patent 3½ years.

To all whom it may concern:

Be it known that I, GEORGE LAWRENCE FISK, a citizen of the United States, residing at Ellisville, in the county of Fulton and State of Illinois, have invented and produced a new and original Design for a Chicken-Fountain, of which the following is a specification.

The invention relates to a new and original design for a chicken-fountain; and it has for its object to provide a design of this character which will be both useful and attractive.

The leading feature of the design consists in the design forming the subject-matter of the accompanying illustration.

5 Figure 1 is a perspective view of a chicken-fountain, showing my new and original design. Fig. 2 is a vertical sectional view of the same.

Referring to the drawings, 1 designates a cylindrical body arranged vertically from a flat base 2, having a greater diametrical extent than the said body and extending beyond the same and provided with a vertical rim 3. The vertical rim 3 is arranged at the periphery of the flat base 2, and completely surrounds the lower portion of the body and is arranged parallel or concentric with the same. The lower portion of the body is provided with an aperture 4, and a horizontal cylindrical mem-

ber 5 extends from the upper portion of the cylindrical body and is located in vertical alignment with the aperture 4. The cylindrical body is provided with a flat circular top 6, and it has an inverted-U-shaped handle 7 arranged centrally of the top. From the upper portion of the cylindrical body, at the side diametrically opposite that at which the cylindrical member 5 is located, is arranged an approximately oblong plate 8, disposed horizontally and located a short distance below the plane of the horizontal top 6. This oblong plate has a straight outer longitudinal edge and straight side or end edges, and the inner longitudinal edge is concavely curved to conform to the configuration of the adjacent portion of the cylindrical body.

Having thus described the invention, what is claimed as new is—

The design for a chicken-fountain, as herein shown and described.

In testimony that I claim the foregoing as my own I have hereto affixed my signature in the presence of two witnesses.

GEORGE LAWRENCE FISK.
